UNITED STATES PATENT OFFICE.

CHARLES L. GANDY, OF MOUNT AUBURN, ILLINOIS.

VALVE-STEM GUARD.

Application filed December 23, 1920. Serial No. 432,743.

To all whom it may concern:

Be it known that I, CHARLES L. GANDY, a citizen of the United States, residing at Mount Auburn, in the county of Christian 5 and State of Illinois, have invented a new and useful Valve-Stem Guard, of which the following is a specification.

This invention relates to an improved valve stem guard, the primary object of the 10 invention being to provide means to eliminate any possibility of sand or moisture entering between the inner tube and casing of a tire, through the valve stem opening.

A further object of the invention is to 15 provide a guard of this character which will brace the valve stem at a point adjacent to its connection with the inner tube associated therewith, to prevent movement of the valve stem with respect to the inner tube.

20 With the foregoing and other objects in view which will appear as the description proceeds, the invention resides in the combination and arrangement of parts and in the details of construction hereinafter described 25 and claimed, it being understood that changes in the precise embodiment of the invention herein disclosed, may be made within in the scope of what is claimed, without departing from the spirit of the invention.

30 Referring to the drawing:

Figure 1 illustrates a sectional view through a rim and inner tube, showing the invention as applied.

Figure 2 illustrates a plan view of the 35 guard.

Referring to the drawing in detail, the reference character 5 designates the felloe of a motor vehicle wheel, which is supplied with the usual valve stem opening to accommodate the usual valve stem which in the present showing is indicated in the drawing at 6.

The inner tube of a tire is indicated at 7 which inner tube is secured to the valve 45 stem 6, by means of the usual bridge 8 and clamping nut 8' that cooperates with the head 9 of the valve stem.

Mounted on the valve stem 6 is the guard 10 forming an important feature of the invention, which guard is formed preferably

of rubber and is provided with a central opening 11 to receive the valve stem 6, the opening 11 being relatively small as compared with the stem 6, so that the walls of the opening will closely engage the stem 55 and prevent moisture from entering the tire, between the stem and stem opening, it being obvious that a fluid-tight connection is formed between the stem and guard.

The guard is also provided with a relatively flat rim engaging surface 12 designed to contact with the inner edge of the rim to insure a water-tight connection at this point, while the opposed surface of the guard is shown as curved as at 13, or dome-shaped 60 to allow the guard to give under the pressure of the securing nut 14 operating on the stem 6, and at the same time provide sloping surfaces to contact with that portion of the inner tube adjacent to the valve stem and 65 hold the inner tube out of contact with the side edges of the bridge washer.

From the foregoing it is obvious that the guard may be readily and easily applied to the usual tire constructions, now in use, and 70 that the same will guard the space between the valve stem and the valve stem opening to exclude all foreign matter.

Having thus described the invention, what 75 is claimed as new is:

In a guard adapted for use with tire valve stems, and bridge washers associated therewith, a body portion formed of rubber material and having a relatively flat circular rim engaging surface and having a dome-shaped opposed surface, the dome-shaped 80 surface of the guard adapted to lie under the bridge washer associated therewith, and said guard adapted to extend beyond the side edges of the bridge washer, a nut on the valve stem for securing the guard and bridge washer against movement.

In testimony that I claim the foregoing as my own, I have hereto affixed my signature in the presence of two witnesses.

CHARLES L. GANDY.

Witnesses:

W. O. BRAMEL,
MASON WISE.
